CLAIM

We claim the ornamental design for a stand light, as shown and described.

DESCRIPTION

FIG. 1 is a perspective view of a stand light in a stowed configuration.

FIG. 2 is a front view of the stand light of FIG. 1.

FIG. 3 is a rear view of the stand light of FIG. 1.

FIG. 4 is a first side view of the stand light of FIG. 1.

FIG. 5 is a second side view of the stand light of FIG. 1.

FIG. 6 is a top view of the stand light of FIG. 1.

FIG. 7 is a bottom view of the stand light of FIG. 1.

FIG. 8 is a perspective view of a stand light in a deployed configuration.

FIG. 9 is a front view of the stand light of FIG. 8.

FIG. 10 is a rear view of the stand light of FIG. 8.

FIG. 11 is a first side view of the stand light of FIG. 8.

FIG. 12 is a second side view of the stand light of FIG. 8.

FIG. 13 is a top view of the stand light of FIG. 8; and,

FIG. 14 is a bottom view of the stand light of FIG. 8.

Portions of the stand light shown in broken lines form no part of the claimed design.

1 Claim, 10 Drawing Sheets
